DESIGN FOR A DIAGNOSTIC INSTRUMENT

Edward M. Splaine, Southbridge, Mass., assignor
to American Optical Company, Southbridge,
Mass., a voluntary association of Massachu-
sets

Application March 24, 1938, Serial No. 76,058

Term of patent 14 years

To all whom it may concern:

Be it known that I, Edward M. Splaine, a citizen of the United States of America, residing at Southbridge, in the county of Worcester and State of Massachusetts, have invented a new, original, and ornamental Design for a Diagnostic Instrument, of which the following is a specification, reference being made to the accompanying drawing, forming a part thereof.

Fig. I is a perspective view of a diagnostic instrument embodying my design;

Fig. II is a front view of the instrument head shown in Fig. I; and

Fig. III is a side view of the instrument head shown in Fig. II.

The characteristic features of my design are shown in full lines and comprise broadly the proportion of parts and contour shape of the reflector hood and support for said hood.

I claim:

The ornamental design for a diagnostic instrument, substantially as shown and described.

EDWARD M. SPLAINE,
